UNITED STATES PATENT OFFICE.

GEORGE STANLEY WALPOLE, OF LONDON, ENGLAND.

ALIGNMENT BAR AND TYPE PROTECTOR FOR USE IN EMBOSSED MACHINES.

Application filed January 31, 1924. Serial No. 689,773.

To all whom it may concern:

Be it known that I, GEORGE STANLEY WALPOLE, of 121 Victoria Street, Westminster, London SW. 1, England, a subject of the King of Great Britain, have invented certain new and useful Improvements in and Relating to Alignment Bars and Type Protectors for Use in Embossing Machines, of which the following is a specification.

10 This invention relates to alignment bars and type protectors, and it relates particularly to such devices for use in embossing machines of the type known as cutter-crush machines, intended to produce embossed 15 words, letters, numerals, designs, or the like, on cardboard or like material, the embossed portions being further generally covered with coloured paper or the like, which is cut out and pressed into recesses formed by the 20 type, by means of cutting edges provided thereon.

The object of the invention is to provide a simple alignment bar, which will serve as an easy and simple means for correctly 25 positioning the cards to be embossed, whilst it also serves for the correct alignment and the protection of the type or embossing dies. Other advantages of the invention will appear from the following description.

30 According to the invention, I provide a positive stop between the card and the pressure member of an embossing machine of the kind described, the dimensions of this stop being such that it takes the pressure 35 when the type has been impressed into the card or the like, to the required extent, and thus prevents the type being damaged. The invention further comprises an improved 40 alignment bar, for facilitating the correct alignment and positioning of the card and type in the machine, and the alignment bar may at the same time with advantage, serve as the stop or type protector referred to. The alignment bar is adapted normally to 45 rest on the press platen, and to be removably secured thereto, in the correct position, by means of lateral members, which when a card is inserted between the platen and the bar, serve as abutments against which the 50 card can be easily and quickly positioned. These lateral members may take the form of downwardly depending bars or the like, one of which is rectangularly secured at each end of the bar, and which are adapted 55 to fit into recesses, or between pins, or be otherwise conveniently secured to the platen.

Other features of the invention will be described hereinafter, and a preferred method of carrying it out, is illustrated in the accompanying drawings, in which:—

60 Fig. 1 is a perspective view of an alignment bar and type protector according to the invention, and

Fig. 2 is a section on the line A—A of Fig. 1, the bar being in this case shown in 65 its operative position with a card.

Figure 3 is a perspective view of one form of an embossing machine, showing the application of the present invention, and

70 Figure 4 is a sectional elevation of the machine shown in Fig. 3, with a card inserted.

75 Referring to the drawings, I have illustrated in Figs. 3 and 4, one form of an embossing or cutter crush machine, to which the present invention is applicable, although the invention is not limited to use with this particular form of cutter crush machine, which per se forms no part of the present 80 invention.

The machine comprises a base plate 6, a table 7, pivoted at 8 to the base 6 and lower platen 2, slidably disposed on the table 7. An upper platen 10 is disposed in fixed but adjustable relationship to the frame, and a cam shaft 11, which may be rotated by means of a hand lever 12 is provided for lifting the table, so that the work may be pressed between the two platens, the cams on the shaft 11 being so adjusted that at 90 their maximum lift, the lower platen 2 is parallel with the upper platen 10. A wedge member 13 is provided in a suitable bridge piece and preferably supported by four columns 14 for adjusting the position of the 95 upper platen 10, and moving it upwards or downwards, but always in a plane parallel to the base.

100 In operation a card or the like is arranged on the lower platen 2, and one or more pieces of embossing type 16, having cutting edges thereon are arranged on the card, with paper of any desired color between the type and the card. The platen 2 is then pushed backwards so that the work will be located beneath the upper platen 10, when pressure is applied by means of the hand lever 12, and when the letters, numerals, or designs of the type used will be embossed on the card and produced thereon with an adhesive covering of the colored paper being employed, the paper preferably 105 pro-

vided with an adhesive backing of any suitable kind.

For the purposes hereinafter described, I provide a positive stop between the pressure member, i. e. in the present case the platen 10, and the card 3, and this positive stop may take the form of an alignment bar, although it may also be provided in other forms. I have found that if this positive stop is constructed of sufficiently great strength, for example, of a metal bar having a flat underside, it acts as a protector for the type in a manner hereinafter described, and that the impression made by the stop on the card is so small as to be practically imperceptible to the naked eye.

In the drawings I have illustrated such a positive stop in the form of an alignment bar. This bar consists of a straight edged bar 1, preferably made of iron, steel, or the like, and adapted normally to rest flat on the platen or table 2, on which the card 3 to be embossed is disposed. Secured at either extremity, and to the under-side of the bar 1, are two transverse downwardly depending side members 4, which are adapted to fit into recesses 5 as shown in Fig. 2 of the drawings, cut in the sides of the table or platen, the length of the bar 1, and the arrangement of the said side members 4 and recesses 5 being such that the bar is normally held rigidly at right angles to the edges of the table or platen 2, and rests on the upper surface of the said table, with the upper edges of the side members flush with the edges of the table. If desired, the recesses referred to as being disposed in the sides of the table, may be replaced by suitably spaced pins 17, as shown in Fig. 2 of the drawings, or other like means, adapted to engage and to hold the said side members. The card 3 to be embossed, is inserted between the platen or table 2, and the alignment bar 1, as illustrated in Fig. 2, whereby the said bar, with its side members 4, is raised by the thickness of the card 3, the side members thus projecting above the edge of the table by the thickness of the card, and thus forming abutments against which the card can easily and rapidly be placed in correct alignment on the table. This arrangement prevents the card from slipping, or from being incorrectly adjusted, the bar being of sufficient weight to hold the card in position.

If desired, the upper face of the alignment bar may be graduated in any convenient manner, to assist in the correct spacing of the type.

I have found that if the type is pressed or punched too far into the card, not only is the impression obtained an imperfect one, but the cutting edges of the type itself are liable to be ruined. I therefore construct my alignment bar of a thickness less than

the height of the type, the difference being the preferred or permissible depth of impression for the type. It follows that when the type has been impressed or punched into the card until its upper surface is flush with the alignment bar, any further pressure put on by the operator will be taken by the rigid alignment bar, and the type thus protected.

If it should be found advisable to use various different sizes or shapes of type or dies in a machine, and that these different sizes or shapes of dies should be preferably impressed into the cards to different thicknesses and depths respectively, then the thickness of the alignment bar is such as to be less than the height of the type by the mean value of the preferred or permissible depths of impression for the different types. Instead of arranging the thickness of the alignment bar to be of the mean value stated, separate alignment bars for various kinds of type could of course be used.

It should be noted that the protection of type forms a material part of my invention, as I have found that other known methods for preventing excess of pressure being put on the type, such as for example, the provision of an adjustable stop, to prevent the pressure handle being moved too far, have proved unsatisfactory. Accordingly I have found that the type is more efficiently protected by inserting a positive stop, in the form of a steel, iron or like bar or member, between the card and the pressure member, this stop being of course arranged with the requisite thickness above referred to. For convenience and simplicity of operation, I use my improved alignment bar to serve at the same time as a type protector, but it should be understood that the insertion between the card and the pressure member of a positive stop for the purpose of protecting the type, does not fall outside the scope of the present invention, even though that stop be not used as an alignment bar.

In addition to providing a rapid means for the correct positioning of the card, the alignment bar also serves to assist in the correct positioning of the type or die, which can either be placed loosely against the bar, or else can be assembled in various units in a suitable type holding device, which latter device when placed against the bar, will automatically be disposed at right angles to the edges of the table, and hence also of the card.

The use of the improved alignment bar has many advantages over other devices which have hitherto been used in connection with embossing machines of the type described. In most of these machines it has been the practice to provide the table with a plurality of suitably spaced lines, with

reference to which both the card, and in some cases also the type, were adjusted.

This operation requires to be done by eye, and it is obvious that the present device, which provides a positive means of adjusting the card by touch, is both more easy and more rapid than that depending on adjustment by eye.

Furthermore, where it is desired to emboss a plurality of figures, letters or the like, in column, the positive adjustment provided ensures the several impressions being correctly aligned one beneath the other.

It will be seen that the improved alignment bar herein described, provides a simple, efficient, rapid and accurate means for holding the card to be embossed, in the correct position with reference to the table, and for continuing to hold it in the same position, through a series of embossing operations, whilst it further provides a means for assisting in the correct alignment not only of the card, but also of the type or dies, a further important feature being that it also serves to protect the type from damage.

Whilst I do not desire the invention to be limited in this respect, I may say that I prefer to use the improved alignment bar in conjunction with a type holding bar of the kind described in my co-pending specifications Nos. 2909/23 and 5202/23, although it is to be understood that the type or dies may, if desired, be arranged in any other convenient manner.

I claim:

1. An alignment bar for use on embossing machines of the kind described, comprising a metal bar, adapted normally to rest on the platen, and to be removably secured in the correct position thereon by means of lateral members, which serve as abutments for positioning the card when the latter is inserted between the platen and the bar.
2. An alignment bar for use on embossing machines, comprising a bar adapted to rest on the platen, means for removably securing said bar in card alignment on said

platen, said means serving to position the card or the like when the latter is inserted between the platen and the bar.

3. An alignment bar for use on embossing machines, comprising a bar adapted to rest on the platen, means for removably securing said bar in card alignment on said platen, said means serving to position the card or the like when the latter is inserted between the platen and the bar, said bar extending above the platen to limit the movement of a pressure member relative to said platen.

4. An alignment bar for use on embossing machines, comprising a bar the same length as the platen and having at each end a downwardly depending rectangularly disposed member adapted to extend over the side of the platen.

5. In combination with an embossing machine having a platen adapted to receive a card and type for embossing on said card, means for exerting pressure on said type, and means for protecting said type comprising a member constituting a positive stop between said card and pressure exerting means.

6. In combination with an embossing machine having a platen adapted to receive a card and type for embossing on said card, means for exerting pressure on said type, and means serving both as an alignment bar for facilitating the correct positioning of the card and type and for protecting said type from undue pressure from said pressure exerting means.

7. In combination with an embossing machine having a platen adapted to receive a card and type for embossing on said card, means for exerting pressure on said type, and a member positioned between and forming a positive stop between the card and pressure exerting means, said member also serving as an alignment bar for facilitating the correct positioning of the card and type.

In witness whereof I have hereunto set my hand.

GEORGE STANLEY WALPOLE.
